UNITED STATES PATENT OFFICE.

WILLIAM KENT, OF JERSEY CITY, NEW JERSEY.

TUBE-SHEET FOR STEAM-BOILERS.

SPECIFICATION forming part of Letters Patent No. 330,127, dated November 10, 1885.

Application filed March 23, 1885. Serial No. 159,897. (No model.)

To all whom it may concern:

Be it known that I, WILLIAM KENT, a citizen of the United States, residing at Jersey City, in the county of Hudson and State of New Jersey, have invented certain new and useful Improvements in Tube-Sheets for Boilers; and I do hereby declare the following to be a full, clear, and exact description of the invention, such as will enable others skilled in the art to which it appertains to make and use the same.

My invention relates to certain novel and useful improvements in tube-sheets for steam-boilers, and has for its object to provide a tube-sheet into which the inclined tubes may be expanded, so as to project from the sheet at right angles; and with these ends in view my invention consists in the details of construction hereinafter fully described, and specifically designated by the claim.

In order that those skilled in the art to which my invention appertains may more fully understand the same, I will proceed to describe its construction, referring by letter to the accompanying drawings, forming a part of this specification, in which—

Figure 1 is a front elevation of a tube sheet constructed in accordance with my improvement, and Fig. 2 a vertical section of the same with the inclined water-tubes expanded in the sheet.

Similar letters denote like parts in the several figures.

A is the tube-sheet, provided with openings B, formed by depressing the stock of the sheet more at the bottom than at the top by a suitable die, and then piercing. The openings thus formed will be in a plane parallel with the plane of the end of the water-tubes C, so that the latter will enter the sheet at right angles.

I preferably form the tube-sheet by compressing a plain sheet between suitable dies, either simple or multiple.

What I claim as new is—

A tube-sheet for boilers, constructed with inclined water-tubes, having the tube holes formed within depressions that are inclined at the same angle with that of the tubes, whereby the latter may project at right angles from that part of the sheet within which they are expanded, substantially as shown and described.

In testimony whereof I affix my signature in presence of two witnesses.

WILLIAM KENT.

Witnesses:

E. CORNWELL,
Wm. E. STELLINGS.
